UNITED STATES PATENT OFFICE.

THOMAS C. HARGRAVE, OF BOSTON, MASSACHUSETTS.

IMPROVEMENT IN REGISTERING STEAM-GAUGES.

Specification forming part of Letters Patent No. 124,816, dated March 19, 1872.

To all whom it may concern:

Be it known that I, THOMAS C. HARGRAVE, of the city of Boston and State of Massachusetts, have invented certain Improvements in Registering Steam-Gauges; and I hereby declare the following to be a full, clear, and exact description thereof, reference being had to the accompanying drawing making a part of this specification, in which—

Figure 1 represents a front elevation of the gauge with the dial removed. Fig. 2 represents a side elevation of a portion of the mechanism. Fig. 3 represents a plan and elevation of the adjusting device. Fig. 4 represents the main indicating-hand. Fig. 5 represents the maximum hand, and Fig. 6 represents a gauge-cock with a locking device.

The object of my invention is to provide a steam-gauge to indicate and register the negligence of an engineer in allowing the steam pressure in a boiler to exceed a determined pressure; and consists in a bar, provided with a star-wheel and screw revolving on the same center with the main hand, and actuating a registering-hand attached to a pinion.

In the said drawing, A is the ordinary gauge-spring, working the pinion b by means of the link a and rack b'. On the frame B rises a pillar, c, which has a groove, c', around it near its top to receive the clasp-spring of the maximum hand k, and is hollow for the spindle a' to pass through and carry the main hand of the gauge z on its end. D is a bar, made as shown in Fig. 3, and has on it standards d d, which serve as bearings for a shaft, e, and has also the spring-clasp d', which slips over and attaches the bar to the pillar c. The shaft e has at one end a star-wheel, g, and at the other a screw, f. The indicating-hand E, Fig. 5, is attached to a pinion and collar, i, and is bent at i', as shown, for the purpose of allowing the main hand with its spring h to pass clear of it. The collar and pinion i are fitted over the pillar c, and the teeth of the pinion engage in the worm of the screw f. Above the collar i in the groove c', by means of a spring-clasp or otherwise, is attached the maximum hand k, and above this is placed the main hand of the gauge z on the head of the spindle a', which slightly protrudes above the pillar c. This main hand z, Fig. 4, is made with a bent spring, h, near its end. A bent spring, o, soldered to the bar D, presses lightly against the shaft e to act as a slight brake

on it and steady its revolutions. The handle to the steam-cock. Fig. 6, is made bent, as shown at P, one arm, x, when the steam is turned on, being vertical to the face of the gauge, and fitting into a depression (not shown) in the rim of the face, the other arm, y, being parallel to the steam-pipe, and having through its end two openings, P' and N, transverse to each other. In the gauge-pipe is a shallow screw-hole, N', corresponding to the hole on the back side of the opening P'. When the steam is turned on, the gauge-face screwed down, and both are to be locked, the handle P is brought into the position shown in Fig. 6, a screw is screwed into the hole N' till its head is flush with the face of the opening P', and a hasp of a padlock introduced into the said opening, the padlock locked, and the head of the screw N' is protected, so it cannot be withdrawn, and the gauge opened, or the steam-cock turned off.

The operation of my gauge is as follows: The steam being turned on, the main hand passes around the dial until the spring h comes in contact with a tooth of the star-wheel, which it pushes before it as it passes. This movement of the star-wheel turns the shaft e and screw f, which turns the pinion i and moves the indicating-hand one space. This operation is repeated each time the main hand passes above any given point at which the star-wheel has been set. The "max" hand k is carried around the dial to the highest point attained by the main hand by means of the spring h engaging it, and is there left, showing the highest pressure reached.

Having thus described my invention, what I claim as new, and desire to secure by Letters Patent, is—

1. The radially-adjustable bar D with the shaft e, having a star-wheel and worm-gear, in combination with the registering-hand E, as set forth, and for the purpose described.

2. In a registering-pressure gauge, the steam-spring A, rack b, pinion b', spring M, frame B with its pillar c and spindle a' and main hand z, in combination with the adjustable bar D and indicating-hand E, substantially as and for the purpose set forth.

THOMAS C. HARGRAVE.
